UNITED STATES PATENT OFFICE.

LEWIS J. ATWOOD, OF WATERBURY, CONNECTICUT, ASSIGNOR TO THE PLUME & ATWOOD MANUFACTURING COMPANY, OF SAME PLACE.

DESIGN FOR A LAMP-BURNER.

SPECIFICATION forming part of Design No. 23,404, dated June 26, 1894.

Application filed May 28, 1894. Serial No. 512,803. Term of patent 7 years.

To all whom it may concern:

Be it known that I, LEWIS J. ATWOOD, a citizen of the United States, residing at Waterbury, in the county of New Haven and State of Connecticut, have invented a new Design for a Lamp-Burner, of which the following is a specification.

The leading feature of this design for a lamp burner consists in the design of the radial and tapering corrugations of the deflector and chimney base.

In the drawings:—Figure 1. is a plan view, and Fig. 2. is a side view of the design for a lamp burner.

The upper part of the burner usually called the deflector is ornamented with radial and tapering corrugations at *a.* and the lower part of the burner usually called the chimney base is also ornamented with radial corrugations at *b.*

I claim—

The design for a lamp burner substantially as shown and described.

Signed by me this 23d day of May, 1894.

L. J. ATWOOD.
